US00D441878S

(12) **United States Design Patent** (10) Patent No.: **US D441,878 S**
Franson et al. (45) Date of Patent: ** May 8, 2001

(54) **WINDOW COMPONENT EXTRUSION**

(75) Inventors: **Jeffrey R. Franson**, Maple Valley, WA (US); **Lorane Goss**, Slippery Rock, PA (US)

(73) Assignee: **Mikron Industries, Inc.**, Kent, WA (US)

(**) Term: **14 Years**

(21) Appl. No.: **29/103,850**

(22) Filed: **Apr. 22, 1999**

Related U.S. Application Data

(62) Division of application No. 29/084,209, filed on Feb. 26, 1998, now Pat. No. Des. 416,628.
